FREE PISTON INTERNAL-COMBUSTION
ENGINE

Evelyn Stewart Lansdowne Beale, Staines, England, assignor to Alan Muntz & Company Limited, Hounslow, England, a company of Great Britain

Application February 16, 1943, Serial No. 476,041
In Great Britain February 2, 1942

14 Claims. (Cl. 123—46)

1

This invention relates to free-piston internal-combustion engines of the kind in which the free-piston assembly consists of a power piston rigidly connected to a piston of larger diameter serving as a compressor piston or as a pneumatic cushion piston or as both. The free-piston assembly is moved through the in-stroke, namely the one that effects compression in the combustion chamber, at least in part by energy accumulated in the pneumatic cushion during the preceding expansion stroke. The cylinders in which these pistons reciprocate are coaxial, and, as they are of different diameters, the clearances between piston and cylinder, required to allow for thermal expansion, are larger for the larger cylinder. Furthermore, as it may be necessary to make the larger piston of an aluminium alloy and the smaller piston of cast iron, the difference in the clearances may be accentuated. Consequently, particularly in an engine in which the axis is horizontal, the piston assembly is apt to tilt in relation to the cylinders in starting from cold, but when the engine is hot and the clearances are taken up, the tilt is eliminated. An object of this invention is to provide an improved arrangement which overcomes such tilting when the engine is cold.

Such engines are usually started by setting the free-piston assembly at its outer dead point and thereafter quickly admitting a charge of air (or other gas) under relatively high pressure into the cushion cylinder. The starting air is released into the cushion at atmospheric temperature. This air then does work on the piston so that its temperature falls. Thus the mean temperature of the cushion air is lower than the temperature of the cushion cylinder walls. After the engine has been running for a short time, the air in the cushion will have become heated until its mean temperature is approximately that of the cylinder walls. Such immediate rise of mean temperature necessarily involves a rise of mean pressure in the cushion. A further object of this invention is to provide an improved arrangement of cushion in which the effect of this pressure rise on starting is at least partly compensated for.

A further object is to provide an improved arrangement for cooling the crown of the piston that operates in the internal-combustion cylinder.

An embodiment of the invention will be described, by way of example, with reference to the accompanying drawings, as applied to a symmetrical type of two-stroke free-piston gas-generator.

2

The term "gas-generator" means a combination of internal-combustion engine and air-compressor in which air from the compressor is used to scavenge and supercharge the internal-combustion engine, the gaseous product of the generator being a mixture of combustion products and air at such a temperature and pressure that it is capable of driving a turbine or other elastic fluid motor which converts the energy of the gaseous product into a mechanical power.

In the drawings:

Fig. 1 is a diagrammatic side elevation of the gas-generator, partly in section on the line 1—1 in Fig. 2,

15 Fig. 2 is a sectional end elevation, the right-hand half being on the line 2R—2R in Fig. 1, and the left-hand half on the line 2L—2L in Fig. 1.

Fig. 3 is a side elevation of the middle portion of the same gas-generator with a part of the casing broken away, and

20 Figs. 4, 5 and 6 are graphs illustrating the operation of this gas-generator.

The generator includes a power cylinder 10 in which operate opposed power pistons 11 and 11A, 25 the cylinder being provided with exhaust ports 12 controlled by the piston 11A and with transfer ports 13 controlled by the piston 11. The power cylinder 10 is disposed within a casing 14 forming a scavenge air receiver for compressed air, 30 which is employed to scavenge the power cylinder. The exhaust ports discharge to a motive gas delivery connection 36.

The power pistons form respectively parts of two identical free-piston assemblies operatively connected together by a synchronising train in 35 known manner. A combined air-compressor and cushion cylinder 15 is arranged co-axially with the power cylinder and attached to one end wall 16 of the air receiver. The outer end of the cylinder 15, the diameter of which is substantially 40 larger than that of the power cylinder 10, is closed by a cover 17 which carries a rigid hollow cylindrical guide 18 projecting towards and co-axially with the power cylinder.

45 The power piston 11 is constituted by a crown and a cylindrical portion or belt 20 which is provided with circumferential grooves for the piston rings and which bears on the power cylinder wall. This piston closes the inner end of a cylindrical sleeve 19 passing through a gland 16' in the end wall 16. The internal diameter of the sleeve 19 substantially exceeds the external diameter of the guide 18. The external diameter of the sleeve 19 is substantially less than that of the ring-car- 50 ryng belt 20 of the piston 11. The outer end of 55

the sleeve 19 has a bore 21 slidably bearing on the guide 18 and an external annular piston 22 co-operating with the compressor and cushion cylinder 15. The inner portion of the cylinder 15 (i. e. that portion nearer the power cylinder) forms the air-compressor chamber, air being drawn in, during the out stroke, through valves such as 23 in the cylinder wall and discharged, during the in stroke, to the receiver, through valves such as 24 in its end wall 16. The outer portion of the cylinder 15 forms the first cushion compartment, while the space within the guide 18 and the sleeve 19 of the piston assembly forms the second cushion compartment.

The guide 18 has hollow walls forming a jacket 25 in which a cooling fluid is circulated, and the inner surface of the guide is provided with fins 26 adapted to assist in cooling the cushion air therein. A pressure-equalising port 27 is provided through the guide near its outer end, communicating between the two cushion compartments. The inner end of the guide is provided with an orifice 28 adapted to direct a jet of air against the under side of the head of the power piston 11 during the in stroke. An inlet poppet valve 29 for starting air is provided in the outer end cover 17 opening into the first cushion compartment.

The starting apparatus is of the standard Pes-cara type, and it includes a starting air chamber 30 mounted on the cover 17 and provided with a cylinder 31 in which operates a piston 32 directly connected to the valve 29, which is adapted to be held on its seat by pressure within the chamber 30. The outer end of the cylinder 31 communicates by a pipe 37 with a 3-way valve 33, which is adapted to close the pipe 37, or to open it to atmosphere, or to put it in communication with a compressed-air reservoir 34. A non-return valve 35 in the piston 32 allows air to pass from the cylinder 31 to the chamber 30. The diameter of the piston 32 exceeds that of the valve 29.

The displaced volume in and the compression ratio of the first cushion compartment in the outer portion of the cylinder 15 are larger than those of the second cushion compartment within the sleeve 19 and the guide 18.

The other end of the engine is identical with that already described, the parts of the other end being denoted in the drawings by the same reference numerals with the addition of A.

The synchronising mechanism constraining the two free-piston assemblies to move equally and oppositely is of the rack-and-pinion type (Figs. 2 and 3). Racks 37 and 37A are rigidly connected, by rods 38 and 38A, to the pistons 22 and 22A respectively. These racks slide in guides 39 and 39A and mesh with a common pinion 40 fixed on a shaft 41. This shaft is journaled in a bearing 42 on the cylinder 10 and in a cover 43 closing an aperture in the casing 14. A cam 44 on the shaft 41 operates a fuel-injection pump 45 supplying a fuel-injection nozzle 47 through a pipe 46. Another pair of racks 37' and 37A', symmetrically opposed, with reference to the axis of the cylinder 10, to the racks 37 and 37A, are connected to the pistons 22 and 22A respectively similarly to the racks 37 and 37A (one of the coupling rods appears in Fig. 2 and is denoted by 38'). These racks mesh with a common pinion 40' fixed on a shaft 41', which may be employed to actuate auxiliary mechanism in a casing 48.

Ducts 49 and 49A open into the first cushion compartments and lead to control means (not

shown) for varying the quantity of air contained in the cushion.

This gas-generator is started as follows. The control valve 33 is operated to admit air from the reservoir 34 (which is charged by any convenient means not shown) to the cylinders 31 and 31A, whence it passes, through the non-return valves, to the starting air chambers 30 and 30A, holding the starting valves on their seats. When these chambers are charged, the control valve 33 is shut. The free-piston assemblies are now moved to their outer dead points in known manner by means not shown in the drawings and the control valve 33 is operated to vent the cylinders 31 and 31A to atmosphere. This release of the air pressure on the outer faces of the starting valve pistons, such as 32, allows the pressure of the air in the starting air chambers acting on the inner faces of these pistons to open the starting valves, so that the starting air is almost instantaneously discharged into the first cushion compartments, where it acts on the pistons 22 and 22A and starts the engine. While the engine is running there will be a certain leakage of scavenging air from the receiver between the power cylinder and the sleeve 19 to the exhaust ports 12 during a part of each cycle, but as in any case the motive gas contains a large quantity of excess air, such leakage is immaterial.

Although the equalising ports 27 and 27A could be of large area, it is preferred to make them of restricted area for various reasons.

Firstly, owing to the pressure drop developed across the cooling jet orifice 28, some air passes from the second to the first cushion compartment that would otherwise assist to raise the velocity of the jet of air cooling the power piston crown. For this reason, the smaller the equalising port is made, the stronger the cooling jet becomes. A high velocity in the cooling air jet entails an increased amount of work, and whereas the work done per stroke varies approximately as the square of the velocity the heat-exchange coefficient is only approximately proportional to the velocity. For this reason, the size of the orifice 28 is selected to limit the air velocity. For example, the maximum pressure drop across this orifice may be between $\frac{1}{2}$ lb. and 2 lbs. e. g. 1 lb. per sq. in.

Secondly, flow of air under the pressure difference between the two cushion compartments represents a pumping loss and performs no useful function when normal conditions are established. It is therefore economical to reduce such loss.

Thirdly, a suitable restriction of the equalising port facilitates compensation for the rise of mean pressure, already referred to, that occurs in the cushion on starting the engine. Fig. 4 shows the temperature variation of the cushion air plotted as ordinate on a base of free-piston displacement between the inner and outer dead points, denoted by IDP and ODP, in a known free-piston engine. Curve S denotes the starting conditions, starting air being admitted at atmospheric temperature T_1 and expanding down to a temperature T_2 with a mean temperature T_m . Under stable running conditions, if the same weight of air remains in the cushion, the temperature variation will be as shown by curve R, from T_1' to T_2' , the mean being T_m' which is substantially higher than T_m . Fig. 5 shows the corresponding pressures, the curve S denoting the starting conditions with the range P_1 to P_2 , and the curve R the running conditions with the range P_1' to P_2' . The compression ratio in the power cylinder

for a given outer dead point varies rather widely with the cushion pressure, and in one particular case investigated it was found that, if no air were released from the cushion while the same indicated work was maintained in the power cylinder (i. e. an approximately constant quantity of fuel was injected at each cycle), the compression ratio in the power cylinder would rise from about 10 to 1 to about 20 to 1, owing to the rise of temperature of the cushion air after the engine was started.

If the equalising port is small, since the whole of the starting air is released into the first cushion compartment, the compression ratio in the power cylinder during the initial cycles will be substantially higher than if the equalising port had been large. Consequently, when a small port is used, the compression ratio in the power cylinder tends to fall as the mean pressures in the cushion compartments become equalised. If the area of the equalising port is suitable, the initial rate of this fall in compression ratio can be made about equal to the initial rate of rise of this compression ratio due to the rise of temperature of the cushion air on starting.

In some designs it may be possible to select the relative areas and clearance volumes of the cushion compartments in such a way as to make the fall in compression ratio due to equalisation of cushion pressures equal to, or slightly larger than, the rise in compression ratio due to temperature rise of the cushion air, so that complete compensation is attained. However, in other designs the range of adjustment of the compression ratio in the power cylinder due to equalisation of cushion pressures is substantially less than the range due to the temperature effect. In such cases it is therefore necessary to provide in known manner additional means for maintaining the compression ratio substantially constant. Such means may automatically release a part of the cushion air, or automatically reduce the quantity of fuel injected which in turn brings the outer dead point inwards. Such controls are likely to suffer from a certain time lag, whereas the pressure equalisation has an immediate effect and reduces not only the speed but also the range of operation required of the automatic control means. This is shown in Fig. 6 in which compression ratio r is plotted as ordinate on a time base. Curve A shows how the compression ratio would rise if there were no leakage of air from the first cushion compartment, and curve B shows how it would fall if there were no temperature rise of the cushion air but the equalising port were operative. Curve C shows how the two effects combine to maintain the compression ratio nearly constant from the time of the first cycle to to the time t_1 when the automatic control gear begins to take effect.

An alternative way of making use of this equalisation effect is to provide in known manner other automatic control means which provide full compensation for the temperature rise of air in the cushion. In this case the effect of releasing the whole of the starting air into the first cushion compartment is to make the compression ratio in the power cylinder substantially higher on the starting stroke than it will be after the cushion pressures have become equalised. This may be useful in ensuring reliable ignition of fuel on the starting stroke when the air charge in the power cylinder will be colder than in subsequent strokes.

I claim:

1. A free-piston internal-combustion engine having a power cylinder, a second cylinder co-axial with and having a diameter larger than that of said power cylinder, a free-piston assembly including a power piston having a ring-carrying belt and rigidly connected by a sleeve to a second piston having a central bore 21, said piston co-operating respectively with said cylinders, and a cylindrical guide rigid with the outer end of said second cylinder and extending co-axially within said sleeve, the internal diameter of said sleeve substantially exceeding the external diameter of said guide, and said free-piston assembly being guided at one end by said belt bearing in the bore of said power cylinder and at the other end of said central bore bearing on said guide, which prevents said second piston from being in the bore of said second cylinder.
2. A free-piston internal-combustion engine having a power cylinder, a second cylinder co-axial with and having a diameter larger than that of said power cylinder, said second cylinder having an inner end wall at its end nearer to said power cylinder and an outer end wall at its end farther from said power cylinder, a cylindrical guide extending co-axially within said second rigid cylinder from said outer end wall, and a free-piston assembly including a power piston having a ring-carrying belt bearing in said power cylinder, a second piston co-operating with said second cylinder and having a central bore bearing on said cylindrical guide, and a cylindrical sleeve rigidly connecting said pistons together and passing through a gland in said inner end wall, said sleeve having an internal diameter which exceeds the external diameter of said guide and said sleeve having an external diameter which is less than the bore of said power cylinder.
3. A free-piston internal-combustion engine having a power cylinder, a pneumatic cushion, a free-piston assembly comprising a power piston co-operating with said power cylinder and a cushion piston forming part of said cushion, said assembly being movable through the stroke that effects compression in said power cylinder at least in part by energy accumulated in said cushion during the preceding expansion stroke in said power cylinder, and the gas space enclosed in said cushion being divided into two compartments communicating with each other by a restricted passage, an inlet for compressed starting gas opening into one of said compartments which has its volume varied by movement of said free-piston assembly, and valve means controlling said inlet.
4. A free-piston internal-combustion engine having a power cylinder, a pneumatic cushion, a free-piston assembly comprising a power piston co-operating with said power cylinder and a cushion piston forming part of said cushion, said assembly being movable through the stroke that effects compression in said power cylinder at least in part by energy accumulated in said cushion during the preceding expansion stroke in said power cylinder, and the gas space enclosed in said cushion being divided into two compartments communicating with each other by a restricted passage, and said compartments having their volumes varied by movement of said free-piston assembly with different effective cushion piston areas respectively, an inlet for compressed starting gas opening into the one of said compartments that has the larger effective cushion

piston area, and valve means controlling said inlet.

5. A free-piston internal-combustion engine having a power cylinder, a pneumatic cushion, a free-piston assembly comprising a power piston co-operating with said power cylinder and a cushion piston forming part of said cushion, said assembly being movable through the stroke that effects compression in said power cylinder at least in part by energy accumulated in said cushion during the preceding expansion stroke in said power cylinder, and the gas space enclosed in said cushion being divided into two compartments communicating with each other by a restricted passage, and said compartments having different ratios of clearance volume to volume swept upon movement of said free-piston assembly, an inlet for compressed starting gas opening into the one of said compartments that has the smaller ratio of clearance volume to swept volume, and valve means controlling said inlet.

6. A free-piston internal-combustion engine having a power cylinder, a pneumatic cushion, a free-piston assembly comprising a power piston co-operating with said power cylinder and a cushion piston forming part of said cushion, said assembly being movable through the stroke that effects compression in said power cylinder at least in part by energy accumulated in said cushion during the preceding expansion stroke in said power cylinder, and the gas space enclosed in said cushion being divided into a first and a second cushion compartment communicating with each other by a restricted passage, an inlet for compressed starting gas opening into said first compartment, and valve means controlling said inlet, said first compartment having a larger effective cushion piston area and a smaller ratio of clearance volume to volume swept upon movement of said free-piston assembly than said second compartment.

7. A free-piston internal-combustion engine having a power cylinder, a cushion cylinder co-axial with and having a diameter larger than that of said power cylinder, a cover closing the end of said cushion cylinder farther from said power cylinder, a hollow cylindrical guide extending co-axially within said cushion cylinder from said cover, a free-piston assembly including a power piston co-operating with said power cylinder, an annular cushion piston co-operating with said cushion cylinder and said guide, and a sleeve rigidly connecting said pistons together, the space between said annular piston and said cover constituting a first cushion compartment and the space contained by said guide, said sleeve and said power piston constituting a second cushion compartment communicating with said first compartment by a restricted passage, and means for admitting a charge of starting air under pressure to said first compartment.

8. A free-piston internal-combustion engine having a power cylinder, a cushion cylinder co-axial with and having a diameter larger than that of said power cylinder, a cover closing the end of said cushion cylinder farther from said power cylinder, a hollow cylindrical guide extending co-axially within said cushion cylinder from said cover and having an inner end wall provided with an orifice, a free-piston assembly including a power piston co-operating with said power cylinder, an annular cushion piston co-operating with said cushion cylinder and said guide, and a sleeve rigidly connecting said pistons together, the space between said annular piston and said

cover constituting a first cushion compartment and the space contained by said guide, said sleeve and said power piston constituting a second cushion compartment, said orifice being placed to direct a jet of gas onto the under side of the head of said power piston, and the space within said hollow guide communicating with said first cushion compartment by a restricted duct, and means for admitting a charge of starting air under pressure to said first compartment.

9. A free-piston internal-combustion engine having a power cylinder, a cushion cylinder co-axial with and having a diameter larger than that of said power cylinder, a cover closing the end of said cushion cylinder farther from said power cylinder, a hollow cylindrical guide extending co-axially within said cushion cylinder from said cover and provided with a jacket for a cooling fluid, said guide having an inner end wall provided with an orifice and said guide having a restricted passage opening out of the outer part of the space within it and leading to the outer part of said cushion cylinder, a free-piston assembly including a power piston co-operating with said power cylinder, an annular cushion piston co-operating with said cushion cylinder and said guide, and a sleeve rigidly connecting said pistons together, the space between said annular piston and said cover constituting a first cushion compartment and the space contained by said guide, said sleeve and said power piston constituting a second cushion compartment, said orifice being placed to direct a jet of gas on the under side of the head of said power piston, and means for admitting a charge of starting air under pressure to said first compartment.

10. A free-piston internal-combustion engine having a power cylinder, a cushion cylinder co-axial with and having a diameter larger than that of said power cylinder, a cover closing the end of said cushion cylinder farther from said power cylinder, a hollow cylindrical guide extending co-axially within said cushion cylinder from said cover, a free-piston assembly including a power piston co-operating with said power cylinder, an annular cushion piston co-operating with said cushion cylinder and said guide, and a sleeve rigidly connecting said pistons together, the space between said annular piston and said cover constituting a first cushion compartment and the space contained by said guide, said sleeve and said power piston constituting a second cushion compartment communicating with said first compartment by a restricted passage, and means for admitting a charge of starting air under pressure to said first compartment, the throttling effect of said restricted passage being such that, after starting, the initial rate of fall in compression ratio in said power cylinder due to equalisation of mean pressures in said compartments is approximately equal to the initial rate of rise of said compression ratio due to the rise of temperature of the cushion gas.

11. A free-piston internal-combustion engine having a power cylinder, a cushion cylinder co-axial with and having a diameter larger than that of said power cylinder, a cover closing the end of said cushion cylinder farther from said power cylinder, a hollow cylindrical guide extending co-axially within said cushion cylinder from said cover and provided with a jacket for a cooling fluid, a free-piston assembly including a power piston co-operating with said power cylinder, an annular cushion piston co-operating with said cushion cylinder and said guide, and

a sleeve rigidly connecting said pistons together, the space between said annular piston and said cover constituting a first cushion compartment and the space contained by said guide, said sleeve and said power piston constituting a second cushion compartment communicating with said first compartment by a restricted passage, and an inner end wall on said guide having an orifice for directing a jet of gas from the interior of said guide onto the under side of the head of said power piston.

12. A free-piston internal-combustion engine having a power cylinder, a second cylinder co-axial with and having a diameter larger than that of said power cylinder, a hollow cylindrical guide extending co-axially within said second cylinder, said guide having an external diameter less than the bore of said power cylinder, a power piston bearing in said power cylinder, an annular piston bearing on said guide and co-operating with said second cylinder, and a sleeve rigidly connecting said pistons together and having substantial clearances from said guide and said power cylinder, said sleeve and said power piston forming with said guide a compression chamber, and said guide having a hollow wall for the circulation therein of a fluid for cooling the contents of said compression chamber.

13. A free-piston internal-combustion engine having a power cylinder, a cushion cylinder co-

axial with and having a diameter larger than that of said power cylinder, a hollow cylindrical guide extending co-axially within said cushion cylinder, a free-piston assembly comprising an annular piston bearing on said guide and co-operating with said cushion cylinder to form a cushion chamber, a power piston bearing in said power cylinder and a sleeve rigidly connecting said pistons together, the space within said guide and said sleeve constituting a second cushion chamber, and means including a communication between said chambers for varying the gas content of both of said chambers.

14. A free-piston internal-combustion engine having a power cylinder, a cushion cylinder co-axial with and having a diameter larger than that of said power cylinder, a hollow cylindrical guide extending co-axially within said cushion cylinder, a free-piston assembly comprising an annular piston bearing on said guide and co-operating with said cushion cylinder, a power piston bearing in said power cylinder, a sleeve rigidly connecting said pistons together and having a clearance from said guide, and control means operable for admitting a charge of compressed starting gas directly into the outer portion of said cushion cylinder, a communication being provided between said outer portion and the interior of said sleeve for transferring gas between said outer portion and said interior.

EVELYN STEWART LANSDOWNE BEALE.
